CLAIM

[21] Appl. No.: 72,185

We claim the ornamental design for a lighting fixture, as shown and described.

[22] Filed: Jun. 12, 1997

DESCRIPTION

[62] Division of Ser. No. 48,303, Dec. 26, 1995, Pat. No. Des. 384,761.

FIG. 1 is a front elevational view embodying our new design for a lighting fixture;
FIG. 2 is a side elevational view thereof;
FIG. 3 is a rear elevational view thereof;
FIG. 4 is a top plan view thereof; and,
FIG. 5 is a bottom plan view thereof.

[51] LOC (6) Cl. 26-05

The broken lines are shown for illustrative purposes only and form no part of the claim design.
